UNITED STATES PATENT OFFICE.

WILLIAM H. FARRIS, OF ROCK ISLAND, ILLINOIS.

STEAM-GENERATOR.

SPECIFICATION forming part of Letters Patent No. 349,426, dated September 21, 1886.

Application filed May 19, 1886. Serial No. 202,673. (No model.)

To all whom it may concern:

Be it known that I, WILLIAM H. FARRIS, a citizen of the United States, residing at Rock Island, in the county of Rock Island and State 5 of Illinois, have invented certain new and useful Improvements in Steam Generators, Circulators, and Pulsators; and I do hereby declare the following to be a full, clear, and exact description of the invention, such as will enable 10 others skilled in the art to which it appertains to make and use the same.

My invention consists in certain novel constructions and combinations of parts, as will be hereinafter described and specifically claimed, 15 whereby a boiler-grate is produced having water-heating and steam-generating hollow grate-bars, hollow fire-bridge with chambers or passage-ways for circulating the water, circulating-pipes, valves, and accommodating joint- 20 connections, which are made water and steam tight by compression, as will be hereinafter set forth.

In the accompanying drawings, Figure 1 is a top view of my invention, showing in section 25 the top portion of the hollow fire-bridge, the rear portions of the side conveying and return pipes, and the rear portion of one of the hollow grate-bars, and also showing the rear portion of the boiler broken away. Fig. 2 is a longitudinal vertical section in the line $x-x$ of 30 Fig. 1. Fig. 3 is a detail view of one of the hollow bosses of the hollow fire-bridge connecting with the grate-bars, showing an inner pipe and central bolt in cross-section. Fig. 4 is a 35 detail view of a hollow boss of the hollow fire-bridge connecting with a side conveying-pipe, showing a central bolt in cross-section. Fig. 5 is a vertical section in the line $y-y$ of Fig. 1. Fig. 6 is an end view of a sliding end support 40 of one of the grate-bars, its bearer being shown in section. Fig. 7 is a front view illustrating my invention. Fig. 8 is an enlarged sectional view of a side pipe, boss of the hollow bridge, a compressible steam-joint connection used in 45 carrying out my invention; and Fig. 9 is a diagram illustrating the same.

The letter A in the drawings represents a boiler, B a grate, and C a fire-bridge. The boiler A is of ordinary construction, having at 50 its portion outside of the furnace-wall a a water-feed pipe, a' , and a circulating-pipe, a'' ,

which latter is by means of a pipe, a^3 , connected with an upper connecting-pipe, a^4 , of the boiler. Near the boiler the pipe a^2 is provided with a cut-off valve, D, by which the circulation is regulated. 55

Between the valve D and pipe a^3 the pipe a^2 is provided with a check-valve, D', by which a return flow of water is prevented.

Between the pipes a^3 a^4 a small check-valve, 60 D², is provided, which is operated by the steam generated in the grate, as will be hereinafter explained. The pipes a^2 a^3 are joined by a T-joint, a^5 , which is connected with another T-joint, a^6 , by means of which it is connected with 65 the end portion, b , of a larger side conveying-pipe or hollow side conveying-bar, b' . The water which circulates from the boiler A through the pipe a^2 and T-joints a^5 a^6 enters the portion b of said conveying side pipe or bar 70 b' and passes into the side pipe or bar b' and into a chamber of the fire-bridge C. The side pipe or bar, b' , is placed next to the side wall of the boiler and above the grate B, and has a downward inclination to the fire-bridge. 75 Owing to this construction said side bar is well exposed to the grate-fire, and steam is thus created, which follows the upward inclination of the side bar and passes into the pipe a^3 below the check-valve D². From time 80 to time the slow inertia of the water below causes this steam to gather force sufficient to open the check-valve D² and pass through the pipe a^4 into the steam-room of the boiler. The water below in the pipes a^3 a^2 thereupon partly 85 follows the flow of steam by lifting the check-valve and entering the T-joint a^5 ; but owing to its weight it enters the side bar b' . The side pipe or bar b' is provided with a heavy 90 end flange, b^2 , in the face of which a groove, b^3 , is provided, the shape of which is cylindrical at the bottom, and flaring, as at b^4 , Fig. 9, at the face of said end flange. Opposite said flange a boss, c , is provided on the hollow fire-bridge C, with a groove, b^5 , flared at b^4 in 95 the same manner as the boss b^2 .

Into the grooves b^3 a ring, E, of double-convex shape in cross-section, is inserted, and rendered steam-tight by means of a compression or clamp bolt, E'. As is seen in the diagram, 100 Fig. 9, the ring E does not extend to the bottom of the grooves b^3 , nor does it have much

bearing-surface in the flared portions b^4 of the said grooves, and by means of this construction I am enabled to make a steam-tight connection between the side pipe or bar b' and fire-bridge C, even should the grooves b^3 not be or remain precisely parallel. The clamp-bolt E' has a dovetailed portion, e , near its head e' , which portion e is fitted into a dovetailed central groove, e^2 , in a lug, c^8 , at the base of the opening of the boss c. By this described dovetail fit the clamp-bolt E' is prevented from turning and from leaving its central position in the side pipe or bar b' , while the head e' prevents the bolt from being pulled longitudinally out of the groove. The clamp-bolt E' extends through the side pipe or bar b' and through the T-joint a^6 , at the outside of which latter it is provided with a nut, c^3 , having a convex joint-bearing surface, e^4 , fitted into a similar concave joint-bearing, e^5 , of the T-joint a^6 . This concave or ball joint is an effective steam-joint, no matter whether the bolt E' is precisely in line with the T-joint a^6 or not. Leaving the side pipe or bar b' , the water enters an end chamber, c' , of the fire-bridge, which communicates with a rear passage-way, c^2 , of the same. The passage-way c^2 extends the whole length of the fire-bridge across the furnace, and communicates with hollow grate-bars b^5 by means of pipes c^3 , suitably fastened to a middle partition, c^4 , of the fire-bridge. By means of said partition the passage-way c^2 is separated from a front passage-way, c^6 , in the fire-bridge, which latter way directly communicates with the downwardly-inclined hollow grate-bars b^5 . These grate-bars are in form of pipes, and are closed at their lower forward ends, and are constructed with transverse grate-lugs b^6 at their top sides, and with flanges b^7 at their open end portions. Bosses c^6 , corresponding with the flanges b^7 , are provided on the front wall of the fire-bridge C, and these bosses, as well as the flanges b^7 , are provided with flared grooves b^3 and joint-rings E, of the same construction as previously set forth in the description of the side bar b' . The bosses c^6 are provided with inner lugs, c^8 , having dovetailed grooves e^2 , into which the similarly-dovetailed end portions, e , of clamp-bolts E' are fitted, the heads e' of which bear against the lug, and thus hold the clamp-bolt longitudinally in place, same as in the case of the bolt used in connection with side bar b' . The clamp-bolts E' extend through the closed end portions, b^8 , of the grate-bars, and are on the outside provided with nuts c^3 , having convex bearing-surfaces e^4 , fitting into corresponding concave bearing-surfaces, e^5 , in the end portions, b^8 . By drawing or turning up the nuts c^3 the ring-joints and nut-joints of the grate-bars become steam and water tight. The water, flowing through the pipes c^3 , enters the forward hollow portions of the grate-bars b^5 , flows back, upward to the fire-bridge, enters the chamber or passage-way c^2 , and flows along the same until it passes through a hollow boss,

c , of the fire-bridge to a return side pipe or bar, b^9 . The end portions, b^8 , of the grate-bars b^5 are provided with dovetailed projections f , which are loosely fitted into dovetailed grooves f^2 of shoes F, these shoes resting upon a transverse bearing-bar, f^2 , of the furnace, and thereby supporting the end portions, b^8 . When the heat expands the grate-bars, the extensions f move forward in the shoes F, which remain unmoved upon the bar f^2 , and when the grate-bars are contracted by being cooled down the reverse movement of the extensions will take place in the shoes F. When any one of the grate-bars is worn out and requires to be removed, the nut c^3 is unscrewed and the bar lifted until the shoe F can be withdrawn, when the grate-bar is tilted below the bar f^2 , and then removed from the fire-bridge. A new grate-bar is moved over the bolt E' and pipe c^3 from below the bar f^2 and set and fastened in place, as above described. The hollow upwardly-inclined side bar b^9 is of the same construction as the side bar b' , and is also fastened by similar means and in a like manner to a T-joint a^7 as is the side bar b' to the T-joint a^6 . The T-joint a^7 is connected with a T-joint, a^8 , to the lower end of which a small blow-off pipe, G, with a cock, g, is attached. The upper end of the T-joint a^8 is connected by means of a pipe, g' , and T-joint g^2 with the upper connecting-pipe, a^4 , and with the pipe a^3 . Between the T-joints a^8 and g^2 the pipe g' is provided with a check-valve, G' , of about the same size as the check-valve D'. When the boiler is filled with water in the usual manner, the side bars, b^9 , the fire-bridge C, and the grate-bars b^5 are also filled with water. When the fire is started under the boiler and upon the grate-bars, the water in the grate-bars, side bars, and fire-bridge becomes heated to a greater degree than the water in the boiler, and consequently steam is developed more rapidly in the said parts than in the boiler. The steam in the grate-bars follows the upward inclination of the bars to the fire-bridge, where it unites with the steam created in the heated sides thereof, and then enters the side bar b^9 . It then moves to the higher end of the said side bar, enters the pipe g' , passes through the check-valve G' , and thence through the pipe a^4 into the steam-room of the boiler. The steam developed in the side bar b^9 moves to the higher end of the same, then up through the pipe a^3 , check-valve D^2 , and pipe a^4 into the steam-room of the boiler. Inasmuch as the amount of steam developed in the side bar b^9 is a great deal less than the steam developed and collected by the side bar b^9 , the check-valve D^2 is made proportionally smaller than the check-valve G' , this proportion being about one to four in the majority of cases. When the boiler is in full operation and a certain quantity of steam has passed through the check-valve D^2 by means of over-pressure in the bars and fire-bridge, the bulk and weight of the water in the said parts will have become decreased, and consequently will

be overbalanced by the weight of water in the boiler, whereupon the check-valve D' will be opened and a fresh supply of water from the boiler caused to enter the side bar b'. This 5 operation of the check - valve D' also takes place when the check-valve G' has admitted steam into the boiler. When the consumption of the steam is uniform, these check-valves operate at regular intervals similar to the 10 pulsations of the human arteries, and their clicking noise can be distinctly heard by the engineer, and they thus serve as useful guides in his manipulations of the feed-pump and furnace-fire, and dangerous casualties will be 15 prevented. When the check-valves D' and G' work too fast, the valve D is fully opened in order to allow a full flow of water to the conveying side bar b' and grate-bars b⁵ and fire-bridge C, and thus prevent overheating 20 of the same. When the check-valves work too slowly, the water-supply from the boiler is diminished by partly closing the valve D. When the check-valves cease to operate, the cock g is opened and part of the contents of 25 the side bar b⁹ blown out, whereby dirt is removed and the steam or water cushioning of the valves is stopped.

At suitable places the apparatus is provided with plugs h, giving access to the several 30 passage-ways, and thus facilitating the cleaning of the same of mud and muddy water.

In employing my improved hollow circulating fire-bridge and hollow grate-bars, as herein described, it will be necessary, on account 35 of the manner in which the boilers are "set," to pass the water into the fire-bridge and therefrom into the grate-bars in different ways. For instance, in case the pipe a² could not be connected to the boiler in the hereinbefore-described 40 manner, it would be practical not to use the T-joint a⁵, and to connect pipe a³ directly to the T-joint a⁶, and under this arrangement the water would be taken by a suitable pipe from the readily-accessible front of the boiler, pass 45 through the stop-valve D and check-valve D', suitably provided on said pipe, and finally be conducted to the passage-way c² of the fire-bridge C by means of a suitable conduit-pipe. Again, in the event that I can use neither of 50 the side bars or pipes b' or b⁹, I would take the steam out of chamber c⁵ through a pipe connecting said chamber with the steam-room of the boiler, and having an upper check-valve, G', a blow-out pipe, G, and valve or 55 cock g, as described.

What I claim is—

1. In a boiler-furnace, the combination of hollow circulating grate-bars b⁵, a hollow circulating fire-bridge, C, communicating hollow side bars, b' b⁹, pipes a² a³ g' a⁴, and a boiler, A, 60 substantially as and for the purpose described.

2. The combination, with a boiler, of the hollow grate-bars, fire-bridge and communicating hollow side bars, check-valves D' D² G', and suitable connecting - pipes and connections 65 thereof, substantially as and for the purpose described.

3. The combination of the boiler A and its connecting parts, side bar b', valve D, and grate water-heater, substantially as and for 70 the purpose described.

4. In a steam-joint, the combination of parts, as b' and C, or other analogous portions of the described apparatus, having cylindrical grooves b³, which are outwardly flared, as at 75 b', joint-ring E, having a double-convex form in cross-section, and a suitable clamping device, substantially as and for the purpose described.

5. The hollow fire-bridge C, having tubular bosses c, grooved lugs c⁸, and flared annular 80 grooves b³, in combination with the hollow grate-bars b⁵, having bosses b⁷ and flared annular grooves b³, a double-convex ring, E, and the bolt E', substantially as and for the purpose described. 85

6. The lug c⁸ of the bridge C, having a dovetailed groove, e², in combination with the hollow communicating side bars or tubes of grate, and bolt E', having a dovetailed portion, e, and head e', and nut e³, substantially as and 90 for the purpose described.

7. The clamps E', nuts e³, having convex faces e⁴, and the T-joints a⁶ a⁷, having corresponding concave seats e⁵, in combination with the connected parts of the described apparatus, substantially as and for the purpose described. 95

8. The grate-bar b⁵, having a dovetailed end projection, f, in combination with a shoe, F, having a dovetailed groove, f', and a supporting bearer or bar, f², substantially as and for the purpose described. 100

9. The hollow fire-bridge C, having passage-ways c' c² c⁵, partition c⁴, pipes c³, and the grate-bars b⁵, substantially as and for the purpose described. 105

In testimony whereof I affix my signature in presence of two witnesses.

WILLIAM H. FARRIS.
